COMBINED CARRYING CASE AND WORK TABLE
FOR SPLICING COAXIAL CABLES

Russell W. Trickle, Jr., Janesville, Wis.

Application February 15, 1955, Serial No. 34,523

Term of patent 14 years

(Cl. D54—14)

FIG. 1

FIG. 2

FIG. 3

FIG. 4

Fig. 1 is a perspective view of the combined carrying case and work table for splicing coaxial cables illustrating my new design, the article being shown with the case closed for carrying;

Fig. 2 is a perspective view of the article showing the case closed and supported on legs;

Fig. 3 is a perspective view similar to Fig. 2 but showing the case in open position for use as a work table. The supporting legs are shown broken away for convenience of illustration; and

Fig. 4 is a front elevation of the article in the open position disclosed in Fig. 3, with the legs shown broken away for the same reason.

I claim:

The ornamental design for a combined carrying case and work table for splicing coaxial cables, as shown.
